TUBE DISPENSING DEVICE

Henry G. Giles, Pittsburgh, Pa.

Application March 14, 1946, Serial No. 654,280

1 Claim. (Cl. 222—101)

1

This invention relates to a tube dispensing device and, more specifically, to a device for squeezing pasty material, such as toothpaste, from a tubular container having collapsible walls.

A wide variety of pasty materials, such as toothpaste, soaps, creams, paints and greases and the like are packaged in tubular containers having collapsible walls of plastic, metal or other suitable material. The contents of any such tubular container is removed by manually collapsing the walls of the container. However, almost invariably the entire contents of a tube cannot be completely removed since some of it remains trapped in wrinkled wall portions, hence there is a waste of such material. Furthermore, such tubular containers do not readily lend themselves for use in public bathrooms and the like since they are somewhat unsightly and require the use of both hands for the dispensing of their contents, furthermore, they are readily portable and easily subject to theft or misplacement.

An object of my invention is to provide a dispensing device for overcoming the above-named difficulties and for effectively squeezing out, in a progressive manner, the entire contents of a tubular container having readily collapsible walls.

A more specific object of my invention is to provide a tube dispensing device that may be readily mounted on a wall and which is effective to progressively squeeze the walls of a collapsible container by a rolling motion of an operating member so as to dispense any desired amount of the pasty contents.

A still more specific object of my invention is to provide a tube dispensing device for squeezing predetermined amounts of pasty material from a collapsible tubular container, which device includes an operating element in the form of a ball, cylinder, or the like, which rolls on one surface of the tube while the tube lies in a channel of a shape corresponding to the operating member so as to progressively collapse the sandwiched walls of the tube into the shape of the channel and thus progressively squeeze out the pasty contents of the tube, depending upon the extent of rolling of the operating element.

Other objects and advantages of my invention will become apparent from a study of the following specification taken with the accompanying drawings wherein:

Figure 1 is a top view of a tube dispensing device embodying the principles of my invention;

Figure 2 is a front view of the device shown in Figure 1 with parts shown broken away;

Figure 3 is a cross-sectional view taken along line III—III of Figure 2;

Figure 4 is a top view, with a portion shown broken away, of a modified form of housing for the device shown in Figures 1 to 3, and

Figure 5 is a cross-sectional view of a modified form of housing from that shown in any of the previous figures.

Referring more particularly to Figures 1, 2 and 10, numeral 1 denotes a housing made of metal, plastic, or other suitable material and shaped somewhat in the form of a hollow cylinder cut in half lengthwise. On diametrically opposite sides of housing 1 are provided racks or tracks 2 and 3 having gear teeth. Located immediately above such tracks are provided smooth surfaced tracks 4 and 5 which confront tracks 2 and 3 but are offset with respect thereto as appears more clearly in Figures 1 and 3. Housing 1 is 20 of semicircular cross-section as shown more clearly in Figure 3. A ball 6 of hard rubber, wood, metal, or any other suitable material, is adapted to roll along the semicylindrical channel formed in housing 1. Such rolling motion 25 is provided by virtue of a shaft 7 which extends diametrically through ball 6 and is rigidly fastened with respect thereto. The shaft 7 has gear teeth extending radially of the axis of ball 6, hence serving to key the ball to the shaft. Portions 7a and 7b of shaft 7 are reduced in diameter and have smooth round surfaces so as to roll on the smooth surfaces of track 4 and track 5, respectively. A handle of knob 8 is fastened to one end of shaft 7 and is restrained from rotary 30 movement with respect thereto by virtue of the keying effect of the gear teeth of shaft 7 extending ining therein.

A tube 10 containing toothpaste, cream, or other pasty material, and which tube has collapsible walls, is inserted through the open top of housing 1 and its tapered top portion is fitted into a correspondingly tapered portion 1a of the housing, the neck of such tube being slid through a slot 1b of the housing so that the tubular member 10 may be inserted without removing its screw-threaded cap 12.

Housing 1 may be provided with an integral arm, such as 1c, having a hole 1d through which a screw or other supporting element may be inserted to vertically support the device on a wall, such as a bathroom wall, in which case the opening of the tubular container 10 would be disposed in a lowermost position.

In operation, the full tube 10 is inserted in 55 housing 1, while the ball is in the extreme right

position, as viewed in Figure 1. When it is desired to squeeze out a little of the pasty contents of tube 10, it is merely necessary to turn knob 8 on its axis so that gear or pinion portions 7e and 7f of shaft 7 will mesh with respect to the rack or gear tracks 2 and 3 so as to positively effect a rolling motion of ball 6 along the semi-circular channel formed in housing 1. The resistance offered by the contents of tube 10 will push the ball upwardly, as viewed in Figure 2, hence causing the smooth shaft portions 7a and 7b to roll along the under surface of smooth tracks 4 and 5. Of course, when the entire contents of tube 10 has been removed, it is merely necessary to roll ball 6 from the extreme left to the extreme right position, as viewed in Figure 1, and then replace the emptied tube 10 with a new tube.

Figure 4 is a top view of a modified form of housing wherein the housing 1 instead of being in the form of a hollow cylinder cut substantially halfway along its length, as in Figure 1, is instead in the form of a complete hollow cylinder having only an opening 1e of somewhat flattened elliptical shape at the top thereof, being merely large enough so that a tubular container may be inserted therethrough. The remaining structure is substantially identical with that shown in the previous figures, except that an additional arm or support member 1f is provided which is similar to 1c of Figure 1 so as to give two points of support for mounting the housing.

A handle 24 pivoted to the housing at 25 may serve as a closure element for selectively covering or uncovering the opening of tube 10 thereby replacing cap 12 of tube 10.

Figure 5 shows, in cross-section, a modified form of operating member which is in the form of a cylinder 20 instead of ball 6 and through the axis of which there extends a shaft 21 non-rotatably secured to the cylinder by the keying effect of the radially extending teeth 21a integrally formed on shaft 21. At one end of the shaft there is rigidly secured a handle or knob 22 which is keyed to a toothed portion of shaft 21 extending therein. The housing 23 has a rectangular cross-section and thus provides a flattened channel including a flat surface along which cylinder 20 may be rolled. Cut-away portions 23b and 23c of shaft 21 are smooth and roll on smooth track surfaces formed in the side-walls of housing 23 while surfaces 23d and 23e of the housing are geared forming racks in geared relationship with the pinion portions 21a and 21b of shaft 21.

The operation of the device shown in Figure 5 is identical with that of the devices shown in Figures 1, 2 and 3, the only exception being that a cylinder is rolled on a channelled track instead of having a ball rolled on a semicircular track. The housing for the structure in Figure 5 should have a semi-cylindrical end surface or head portion to conform to the contour of the roller.

It will be apparent to those skilled in the art that the rolling or operating member may have

shapes other than that of a ball or cylinder such as elements of frustoconical or trapezium cross-section.

While I have illustrated and described certain specific embodiments of my invention, it will be understood that this is by way of illustration only and that various changes and modifications may be made within the contemplation of my invention and within the scope of the following claim.

10 I claim:

A device for dispensing the pasty contents of a collapsible-walled tubular container, comprising a hollow cylindrical housing member having a pair of integrally formed racks whose teeth are disposed longitudinally and at diametrically opposite portions of said housing member, and having a pair of integrally formed tracks confronting said racks in spaced parallel relationship but being offset laterally with respect thereto, a ball-shaped operating member having a shaft extending centrally therethrough in fixed relationship and having pinion portions that mesh with said racks and having smooth portions that are adapted to roll on said tracks, and a handle secured to the end of said shaft for manually rotating the shaft so that by virtue of the rack-and-pinion drive said ball-shaped operating member will roll longitudinally inside said housing member so as to squeeze out the contents of said container sandwiched between said operating member and housing and set up reaction forces on said tracks, the radius of the ball-shaped member plus the double thickness of the container wall being substantially equal to the radius of said housing member, said housing member having an opening disposed longitudinally on one side thereof that is sufficiently large as to allow introduction of the tubular container therethrough when said ball-shaped member is in a retracted position, said housing having a neck portion at one end thereof into which a correspondingly shaped neck portion of the container will snugly fit and which is sufficiently large so that the ball-shaped member can be rolled therein to squeeze out the entire contents of the container, said neck portion having a longitudinal slot through which the neck portion of said tubular container may be slid when introducing the container through said longitudinal opening.
